ADJUSTABLE PLIERS

Walter J. Johnson, Buffalo, N.Y., assignor to United-Greenfield Corporation, Chicago, Ill., a corporation of Delaware

Filed Apr. 15, 1960, Ser. No. 22,484
3 Claims. (Cl. 81—410)

This invention relates to adjustable pliers and more particularly to ratchet means for variably limiting separation of the jaws of the pliers while allowing free relative pivoting thereof.

Various different types of adjustable pliers have heretofore been proposed but have generally provided an extremely limited range of adjustment or have been difficult to adjust. In one such pliers, a pivoted step cam pivoted on one of the handle members and engageable with the other handle member is employed to adjust the effective distance between the jaws. This construction gives a relatively wide range of adjustment and is relatively easy to adjust but is expensive to manufacture and is easily damaged in use since the cam is exposed between the handle members.

It is accordingly one object of the present invention to provide adjustable pliers which provide a wide range of adjustment and are easy to adjust and which are relatively inexpensive to manufacture and extremely rugged and reliable in use.

Another object is to provide adjustable pliers in which one handle member is formed with a series of spaced ratchet steps selectively engageable by a pivoted pawl to limit separation of the jaws on the handle members.

According to a feature of the invention, the handle members are formed with interengaging parts to limit separation thereof to an amount such that the pawl lies at all times substantially within the outline of one of the handle members to be protected thereby against damage.

According to another feature of the invention, the pawl may be formed of a single piece having a stepped end engageable with the ratchet steps or of a plurality of separate pieces of different lengths selectively engageable with the ratchet steps. These constructions provide a greater flexibility of adjustment without increasing the number of ratchet steps or complicating the structure.

The above and other objects and features of the invention will be more readily apparent from the following description when read in connection with the accompanying drawings, in which:

FIGURE 1 is a partial perspective view of adjustable pliers embodying the invention;

FIGURE 2 is a side elevation of the pliers of FIGURE 1;

FIGURE 3 is a partial section on the line 3—3 of FIGURE 2;

FIGURE 4 is a view similar to FIGURE 2 showing a different position of adjustment; and

FIGURE 5 is a partial section illustrating an alternative construction.

The pliers, as shown in FIGURES 1 to 4, comprises a first elongated handle member 10 formed at one end with an offset 11 which has integrally formed on the outer end thereof a jaw 12. The handle member 10 and the offset 11 are thinned with respect to the major portion of the handle member and the jaw, as clearly seen in FIGURE 1, and the juncture of the thinned portion with the handle member is formed into a series of ratchet steps 13. The offset 11 is formed for slidable mounting of a second handle member thereon and in the construction shown has an elongated slot 14 formed therein extending substantially at a right angle to the face of the jaw 12.

A second elongated handle member 15 having a jaw 16 rigidly formed therewith crosses the offset 11 of the

2

first handle member and is pivotally connected thereto. As best seen in FIGURE 1, the crossing portion of the second handle member 15 is thinned so that the combined thickness of the crossing portions of the two handle members is substantially equal to the thickness of the handle members and the jaws.

The handle members are pivotally connected together by a pin 17 which is secured to the handle member 15 and which extends slidably and rotatably through the elongated slot 14. The pin 17 may be headed at one end and may carry a nut 18 at its opposite end to prevent it from slipping through the slot 14 or the opening in the handle member through which it extends while at the same time it provides a pivotal connection between the handle members.

The pin 17 pivotally carries an elongated pawl 19 which is pivoted at one end on the pin 17 with its opposite end extending toward the ratchet steps 13 selectively to engage the same. The pawl is adapted to be urged into engagement with the ratchet steps when the handle members are moved together toward their gripping position by a spring which is shown as an elongated leaf spring 21 secured at one end to the free end of the pawl and engageable at its opposite end with the handle member 15 adjacent to the jaw 16 thereon to exert resilient pressure on the pawl when the handle members are moved toward each other.

According to a feature of the invention, the free end of the pawl is formed with a plurality of steps 22 which are selectively engageable with the same ratchet steps 13 thereby providing greater flexibility of adjustment without adding to the number of parts or increasing the complexity of the pliers.

In use the handle members may be separated, as shown in dotted lines in FIGURE 2 and in full lines in FIGURE 4, to move the pawl 19 out of engagement with the ratchet steps 13 so that separation of the jaws can easily be adjusted. For this purpose, the handle member 15 is formed adjacent to the jaw 16 thereon with a projection 23 which will engage the pawl and swing it away from the ratchet teeth when the handle members are moved apart. With the handle members in this position, the pin 17 can be slid to any desired position in the slot 14 to adjust the separation of the jaws 12 and 16. When the handle members are moved toward each other the pawl will swing back into engagement with one or the other of the ratchet teeth under the influence of the spring 21 to limit further separation of the jaws. This action will occur during the initial part of the swinging movement of the handle members and during the final movement of the handle members the jaws will be moved pivotally toward each other to grip between them a nut or other object to be gripped.

According to another feature of the invention, the pawl is so constructed and arranged that it lies at all times substantially within the outline of the handle member 10 and offset 11 to be protected thereby against accidental damage. The maximum outward position of the pawl is illustrated in dot-dash lines in FIGURE 2 and even in this position the major portion of the pawl is protected by the handle member 10 and offset 11.

In order to limit outward movement of the pawl the handle members are formed with interengaging parts to limit separation thereof. As shown, the jaw 16 where it joins the handle member 15 provides a shoulder 24 which will engage the outer surface of the offset 11 when the handle members are moved apart to limit separation thereof. The outer surface of the offset is so contoured that the handle members can never be separated in any of the relative adjusted positions thereof to an extent such that the pawl will be fully exposed where it would be likely to be damaged.

In the alternative construction, illustrated in FIGURE 5, only the handle member 10, the offset 11 and jaw 12 are illustrated, these parts being identical to corresponding parts shown in FIGURES 1 to 4 with the difference being in the construction of the pawl. As shown in FIGURE 5, the pawl is formed by a pair of elongated bars 25 and 26 of different lengths both pivoted at one end on the pin 17 and selectively engageable at their opposite ends with the ratchet steps 13 on the handle member 10. Each of the pawls, as shown, carries a leaf spring 27 engaged by the handle member 15 in the same manner as the spring 21 of FIGURES 1 to 4 to urge the pawls 25 and 26 toward the ratchet steps. The two ratchet members function in essentially the same manner as the steps 22 on the end of the ratchet member 19 for selective engagement with the ratchet steps 13 to provide greater flexibility of adjustment with a minimum of complication of the structure.

While two embodiments of the invention have been shown and described herein, it will be understood that they are illustrative only and not to be taken as a definition of the scope of the invention, reference being had for this purpose to the appended claims.

What is claimed is:

1. Adjustable pliers comprising a first handle member offset adjacent to one end and a jaw member rigidly carried by the offset, a second handle and jaw member crossing the offset, means pivotally and slidably interconnecting the offset and the second handle and jaw member for movement of the pivotal connection along the offset, a series of spaced ratchet steps integrally formed on and across one side of the first handle member adjacent to the offset, an elongated straight pawl pivotally connected at one end to said means and extending along said one side of the first handle member and offset and selectively engageable at its other end with the ratchet steps variably to limit movement of the pivotal connection thereby to limit separation of the jaw members, spring means acting between the second handle member and the pawl urging the pawl toward engagement with one of the ratchet steps when the handle members are moved relatively together, and a part on the second

5 handle member engageable with the pawl when the handle members are moved apart to move the pawl away from the ratchet steps, the handle members including inter-engaging parts to limit separation thereof such that the pawl will remain at all times substantially within the outline of the first handle member and offset to be protected thereby.

2. The pliers of claim 1 in which the pawl provides end portions spaced different distances from said means

10 and selectively engageable with the same ratchet steps.

3. Adjustable pliers comprising an elongated first handle member having an offset adjacent to one end and a jaw member rigidly carried by the offset, the offset having an elongated slot therein at right angles to the jaw member, a second integral handle and jaw member crossing the offset, a pivot pin carried by the second handle and jaw member and fitting slidably and rotatably in the slot, a series of ratchet steps integrally formed on and across one side of the first handle member adjacent to the offset, and elongated pawl pivoted at one end on the pivot pin and extending along said one side of the first handle member and offset and selectively engageable at its other end with the ratchet steps, a spring acting between the second handle member and the pawl urging the pawl toward the ratchet steps when the handle members are moved together, and a part on the second handle member engageable with the pawl when the handle members are moved apart to move the pawl away from the ratchet steps, the second handle including a part engageable with the offset to limit separation of the handle members whereby the pawl will remain at all times substantially within the outline of the first handle member and offset to be protected thereby.
